UNITED STATES PATENT OFFICE.

EDWARD SHALLOW, OF PHILADELPHIA, PENNSYLVANIA, ASSIGNOR, BY MESNE ASSIGNMENTS, TO THE UNITED STATES GAS AND FUEL COMPANY.

HYDROCARBON-BURNER AND COMBINED SUPERHEATER.

SPECIFICATION forming part of Letters Patent No. 403,963, dated May 28, 1889.

Application filed October 13, 1888. Serial No. 287,990. (No model.)

To all whom it may concern:

Be it known that I, EDWARD SHALLOW, a citizen of the United States, residing at Philadelphia, county of Philadelphia, and State of Pennsylvania, have invented certain new and useful Improvements in Hydrocarbon-Burners and Combined Superheaters, of which the following, taken in connection with the drawings hereto, is a full, clear, and exact description.

The object of my invention is to transmute liquid hydrocarbons into the most available condition for combustion and combining therewith elements in such manner and proportion as will superinduce the mechanical action and obtain as available all the heat units contained in the liquid element.

By experience I have learned that for an atomizing element steam is good so far as regards the completeness of the atomization of the liquid at the point of contact; but when the fact is taken into consideration that immediately after point of contact there is a considerable condensation of the steam, and, in addition, that in order to effect atomization the quantity of steam is necessarily large and such large volume detracts by absorption greatly from the quality of the fire as a heating agent, and also by its presence injures and "blankets" the fire, because the atomized oil being held in suspension in the large volume of uncondensed steam each atom or small particle of oil is surrounded with its own atmosphere of water-vapor, and, in consequence, when fire is applied to the atomized mixture the air oxygen, as supporter of combustion, is only brought in contact with the exterior portion of the atomized mixture, the interior portion being inaccessible because of the excess of water-vapor surrounding each particle of oil. Thus, as a result, is obtained a bright white envelope of fire surrounding a black interior, from which the valuable elements pass off unconsumed, being neither raised to the temperature of combustion nor supplied with oxygen to effect mechanical combination; but such portions of the mixture as were supplied with atmospheric oxygen evolved great heat in their combustion

with the presence of the small amount of steam on the exterior, because in the process of combustion a limited quantity of steam may be decomposed and its valuable heating constituent added to the heat of the fire. In the atomization of liquid hydrocarbon by means of compressed air the conditions are entirely changed. In this case each atom of oil is surrounded by the element necessary for its combustion, whence the whole of the oil is burned, and none of the valuable matter passes off unconsumed, a total loss. Still, in using compressed air necessarily no value is received from the decomposition of steam, which of itself is obviously disadvantageous, and, moreover, the first cost of an air-compressor is so great as to render such a system almost entirely valueless in a practical and commercial form.

In my invention I have constructed an apparatus with a view of simplicity, durability, and cheapness, combining the valuable points of both systems sketched above and eliminating the detrimental effects of either.

In the accompanying drawings, Figure 1 illustrates a vertical longitudinal elevation. Fig. 2 illustrates a vertical longitudinal section. Fig. 3 illustrates a front elevation. Figs. 4, 5, and 6 illustrate details of construction. Fig. 7 illustrates combined burner and superheater in operation, attached to a horizontal tubular boiler, and is a vertical longitudinal view, part in section. Fig. 8 illustrates a modification in construction for the purpose of burning gaseous fuel.

Referring to the drawings, wherein corresponding parts are designated by the same letters of reference, A designates a casing, made of any suitable cast material, provided at its forward end with threaded connections, whereby is attached the superheater B, and provided at the rear with the circular adjustable plate or register a, containing ports for the admission of air, said casing A also provided with suitable threaded connections for the air-pipe F and oil-pipe N, as shown in Fig. 2.

B designates a superheater attached, as described, to the casing A, and provided with

superheating-coils C and D for air and steam, respectively, and is provided with a valved port, b' , whereby a lighted taper may be introduced to the interior of superheater for the purpose of initial ignition in the operation.

b designates a tube connected to the superheater-shell B, inclining forward at an angle and communicating with the exterior atmosphere and the interior of the superheater and combustion-chamber.

G designates an inner casing supported at its forward end by legs or spiders g, and provided with suitable connections for the steam-pipe E and the operating-valve L.

H designates a perforated plate cast solid at both ends, at its forward end fitting closely by ground joint within the casing G and containing a series of graduated nozzles and provided with suitable connections, with the operating-valve L, whereby the plate H may be reciprocated longitudinally.

l' designates the port of the operating-valve L.

25 K' designates a series of graduated nozzles secured to the perforated plate H by means of suitable threaded connections, and the outlet of each, except the last, extending within or to the inlet of the one immediately preceding, the diameter of the interior passage of each being smaller than the diameter of the exterior passage of the nozzle immediately preceding, with the exception of the last nozzle, which terminates within the circular annular chamber n, formed by the interior walls of the casing M.

g' designates an inner air-pipe communicating with the air-pipe F and the interior of the casing G.

40 g^2 designates a lift-check valve.

k designates the last one of the series of graduated nozzles extending within the casing M, fitting so closely at its entrance therein as to make a tight joint and extending to the circular opening m, with which the casing M is provided, the inner sides of the walls of which opening are so constructed as to form a seat for the forward end of nozzle k. Thus the size of the outlet from the chamber n to the circular opening m may be regulated by the movement of the nozzle k in obedience to the operation of the valve L.

N designates an oil-pipe passing through the casing A to within the casing M and communicating with the chamber n and a suitable oil-supply tank situated on a lower level.

While I have described a particular means for supporting the graduated nozzles, it will be apparent to any mechanic that an equivalent thereto may be provided in the shape of spider frames, lugs, or projections—in fact, any means whereby these nozzles are held in place in the order named.

In operating my apparatus, the superheating-coil D being put in communication with the steam-dome of a boiler, the valve L being opened, the steam passes through the super-

heating-coil D into the steam-pipe E, through the port l' , into the first one of the series of graduated nozzles. This small quantity of steam entering into the second one of the series of nozzles causes a vacuum at the inlet of said nozzle and draws thereto air through the superheating-coil C into the air-pipe F through the inner pipe, g' , communicating within the casing G and in open communication with the series of graduated nozzles K', and this air, mixing with the steam, has imparted to it a portion of the steam's energy.

Thus there issues from the outlet of this nozzle a mixture of air and steam, considerably increased in volume from the original volume of steam, containing the same amount of energy, with a slight decrease of pressure. This operation is repeated in each of the nozzles, the volume of air being 75 8c

constantly augmented and continually receiving a transferred pressure, whence at the outlet of the nozzle k is obtained a mixture consisting, for the major part, of air, with a small and proper amount of steam, that may be 90 readily decomposed in the process of combustion. This mixture, issuing from the nozzle k and through the circular annular opening m, causes a vacuum within the chamber n and draws the oil through the oil-pipe N, communicating with the chamber n and a suitable oil-supply tank. Issuing through the circular annular opening the atomized material is 95 100

ignited within the superheater attached. Practically, with a diameter of three thirty-seconds of an inch for the steam-outlet, a suction may be induced overcoming six and one-half pounds pressure on the pipe g' in Fig. 2, the diameter of which is three-eighths of an inch, and forming a mixture of the combined 105 volumes, exerting a pressure of twenty pounds at the outlet of the nozzle k; or, put on a different basis, steam-outlet three-thirty seconds of an inch in diameter superinduces an atomizing mixture of sufficient force and volume to 110 perfectly atomize eight and one-half gallons of oil per hour, creating a vacuum within chamber n sufficient to raise the oil four feet—steam-pressure at boiler sixty pounds; specific gravity of oil, 35° Baume.

In order that all the elements might be at proper temperature to effect the most economical result, the apparatus is so devised that both air and steam are raised to a high and equal temperature before admixture, and on this account upon combining the two elements there is no condensation of the steam.

The form of superheater that I prefer to use is in the form of a hollow frustum of a cone with the base of the frustum at the forward end. Encircling this, within the metal of the shell, are placed the superheating-coils. When the fire shall have been started within the superheater, the metal of the shell becomes visibly heated, and this heat is imparted to the superheating-coils by induction. By thus preventing direct contact of the coils with the fire the superheating device is rendered practically indestructible.

When needed, air may be supplied to the fire through the ports of the adjustable plate *a*, and may also be supplied to the interior of the fire through the tubes *b*, extending within 5 the interior of the combustion-chamber.

By reason of the peculiar construction of the apparatus the regulated and perfect admixture of steam and heated air, the thorough commingling of the particles of oil with the 10 very element necessary to complete its combustion, and by reason of the shape of the superheater, which of itself forms a mixing and combustion chamber, the fire produced is almost a non-luminant, burning with a bluish 15 tinge and resembling what is commonly known as a "Bunsen flame," acknowledged to be a fire both efficacious and economic.

I have found a modification of my apparatus of great value in the burning of gas, the capability of supplying the gas with a regulated 20 amount of heated air being second in importance only to the benefits derived from imparting a necessary energy or velocity to the flame, according to the quality of the work to be performed, and as an automatic device to draw to 25 itself any desired volume of gas where artificial pressure may be low or the flow rendered sluggish by long-distance piping.

I am aware that in the present state of the 30 art a series of nozzles is not new, even that a series of graduated nozzles is old in tuyeres, as in Letters Patent No. 329,776, dated November 3, 1885, and many of the steam-injector patents; but I wish to call special attention to 35 the fact that the construction of such would render them not only impracticable, but absolutely impossible to effect the result obtained by my apparatus. These are constructed either to induce a slow current for mixture 40 under atmospheric pressure or to generate a forced current of a liquid, it being desirable that the generating-force be condensed in the operation. The use to which my series of graduated nozzles is put is so radically and 45 obviously different that a casual observation will detect it.

The construction is so arranged that the intense force or energy of a vapor is communicated or transferred to an entirely different 50 gas or vapor of a much greater volume, which is itself in turn used as the atomizing element of a liquid, and by special construction the non-condensation of the primal element is prevented. It is principally upon this intermediate step--viz., the transfer of energy 55 to accomplish a specific object--that the value of my invention is based, together with proper means for the utilization of the transferred energy, and, as mentioned before, the accomplishment of this would be impossible by present methods by virtue of this very difference in construction.

What I claim, and desire to secure by Letters Patent, is--

65 1. In a hydrocarbon-burner, the combination of an outer casing, an inner casing pro-

vided with a series of graduated nozzles and means for supplying air and steam thereto, a circular annular chamber having an exit-orifice and surrounding the outer nozzle, and 70 means for supplying oil thereto, substantially as described.

2. In a hydrocarbon-burner, the combination, with the casing having a series of graduated nozzles and means for supplying air and 75 steam thereto, of a circular annular chamber having an exit-orifice and surrounding the outer nozzle, and means for supplying oil thereto, substantially as described.

3. In a hydrocarbon-burner, the combination of the casing provided with a perforated plate containing a series of graduated nozzles and means for supplying air and steam thereto, a circular annular chamber having an exit-orifice and surrounding the outer nozzle, and 85 means for supplying oil thereto, substantially as described.

4. In a hydrocarbon-burner, the combination of an outer casing, an inner casing provided with a perforated plate containing a 90 series of graduated nozzles and means for supplying air and steam thereto, a circular annular chamber having an exit-orifice and surrounding the outer nozzle, and means for supplying oil thereto, substantially as de- 95 scribed.

5. In a hydrocarbon-burner, the combination, with the inner casing having a perforated plate containing a series of graduated nozzles, of means for supplying air and steam 100 thereto, a circular annular chamber having an exit-orifice and surrounding the outer nozzle, and means for supplying oil thereto, substantially as described.

6. In a hydrocarbon-burner, the combination of a superheater provided with encircling superheating-coils and means for supplying thereto the material to be superheated, an outer casing, an inner casing provided with a 105 series of graduated nozzles and means for supplying air and steam thereto, a circular annular chamber having an exit-orifice and surrounding the outer nozzle, and means for supplying oil thereto, substantially as described.

7. In a hydrocarbon-burner, the combination of a superheater provided with encircling superheating-coils and means for supplying thereto the material to be superheated, an outer casing, an inner casing provided with a 110 perforated plate containing a series of graduated nozzles, means for supplying air and steam thereto, a circular annular chamber having an exit-orifice and surrounding the outer nozzle, and means for supplying oil thereto, substantially as described.

8. In a hydrocarbon-burner, the combination, with the casing having a perforated plate containing a series of graduated nozzles, and an annular oil-chamber connected thereto, as described, of the steam-supply pipe, and a regulating-valve connected to the perforated plate, 115 whereby the flow of steam to the series of 120

130

nozzles and the oil-supply to the combustion-chamber may be regulated, substantially as described.

9. In a hydrocarbon-burner, the combination, with the outer casing, an inner casing having a perforated plate containing a series of graduated nozzles, and an annular oil-chamber connected thereto, as described, of the steam-supply pipe, a regulating - valve connected to the perforated plate, whereby the

flow of steam to the series of graduated nozzles and the oil - supply to the combustion-chamber may be regulated, and an air-supply pipe communicating with the interior of the inner casing, substantially as described.

EDWARD SHALLOW.
